UNITED STATES PATENT OFFICE.

MILTON W. HAZELTON, OF NEW YORK, N. Y.

STEAM-SUPPLYING APPARATUS.

SPECIFICATION forming part of Letters Patent No. 236,810; dated January 18, 1881.

Application filed November 12, 1880. (No model.)

To all whom it may concern:

Be it known that I, MILTON W. HAZELTON, of the city, county, and State of New York, have invented a new and Improved System 5 for Supplying Steam for Power and Heating Purposes, of which the following is a specification.

The invention consists in combining with a heating-tank certain instrumentalities, herein- 10 after described, for the purpose of supplying steam for power or heating purposes.

The drawing represents a front elevation of the device, partly in section.

In the drawing, A represents the central 15 steam-generator or nest of boilers, that is designed to be filled with water, to the exclusion of any steam-space.

B is a pipe, designed to be of any desired 20 length, and to be suitably jacketed to prevent radiation, leading from the top of the generator A to a reservoir or sub-station, C, which consists of a strong iron cylinder provided with a safety-valve and steam-escape or distributing pipes. The pipe B is provided with 25 suitable regulating cocks or valves *a* at either end, for the convenience of the operators in charge of the central and sub-stations, and a pump, B', may be used in connection with said pipe B, wherever it may be required, to force 30 the hot water from the central station, A, to the sub-stations C. From this reservoir or station C is a return-pipe, F, provided with suitable cocks or valves *b*, and a pump, G, connecting with the mud-drum H of the central 35 generator or station, A, from which drum H a pipe, I, connects directly with the said central generator or station, A.

It is designed to fill the generator A and pipe B with water, and also the reservoir or 40 sub-station C, up to the level of the pipe F, and also the return-pipes and drum F I H, and then to supply heat to the water in the generator A, and force the water into circulation through the pipes and vessels B C F H I, either 45 by the pumps herein shown or by steam-pressure, back to said generator A, so that the water

shall part with its steam only within the reservoir or sub-station C, whence said steam will be supplied, through distributing-pipes, to the factories or dwellings requiring it for power or 50 heating purposes. What volume the water loses by the escape of steam from the sub-station C is supplied by a feed-pump, L, through the drum H, or directly to the generator A.

It is designed to construct a comparatively 55 large generator A, and to apply the heat to it in the most effective and economical manner, and to maintain a constant steam-pressure within the said generator of one hundred pounds, or thereabout, per square inch, and to 60 construct one or more comparatively small sub-stations or reservoirs C, having ample steam-space, however, through the bottom of which the hot water shall flow in its circulation through the system of pipes, and in which 65 the steam, or a portion of it, from the water shall escape, thereby maintaining a sufficient steam supply and pressure for the purposes for which it is designed.

If the sub-stations be set much higher than 70 the central station, a pump may be required to force the water from A to C. If the stations be on a level, a pump may be required to force the water from C to A. By using both pumps, B' G, a more rapid circulation of the water can 75 be set up at any time.

Having thus described my invention, I claim as new, and desire to secure by Letters Patent—

In a steam-supply apparatus for power and 80 heating purposes, the combination, with the heating-tank A, of the pipe B, pump B', steam-generator C, having safety-valve, and connected with distributing-pipes, the return-pipe F, pump G, drum H, pump L, and return-pipe I, all arranged substantially as shown and 85 described.

MILTON W. HAZELTON.
